DRILLING MACHINE

Regis T. Carroll, Coraopolis, Pa.

Application December 30, 1944, Serial No. 570,681

3 Claims. (Cl. 77—22)

1

This invention relates to a drilling machine and more particularly to such a machine particularly adapted for drilling airplane parts.

In airplanes of the small transport size and larger, there are a great number of more or less flat bulk heads having one to two hundred holes of various sizes which must be drilled. There are also a great number of small assemblies of various types. Most of these assemblies and bulk heads have different arrangements of holes therein and, therefore, it is impractical to have a multiple drill jig for each assembly.

The present practice is to drill each hole separately through drill bushings in a drill plate. In each assembly the drill may be changed as high as ten times due to the various sizes of rivets and bolts being used, this being a very slow and expensive operation.

It is an object of my invention to provide a mass drilling machine that can be used on many different assemblies.

This and other objects will be more apparent after referring to the following specification and attached drawings, in which:

Figure 1 is an elevation partly in cross section of the drilling machine;

Figure 2 is a plan view of the rotary table removed from the machine;

Figure 3 is an enlarged view in elevation of the upper end of one of the drill spindles;

Figure 4 is an enlarged vertical sectional view through one of the spindles and its supporting connection;

Figure 5 is a horizontal sectional view to an enlarged scale taken on the line V—V of Figure 1; and

Figure 6 is a view similar to Figure 5 showing a modified form in which the drill guide platen is mounted for adjustment for correcting misalignment between spindle centers and work to be drilled.

Referring more particularly to the drawings, the reference numeral 12 indicates a machine frame having a slide 14 at its upper end in which is mounted a gear box 16 having a plurality of drive shafts 18 extending therefrom. The gear box may be of any standard type having means for rotating the various shafts 18 at the same or different speeds. Power is provided to the gear box by motor 20 mounted thereon through the shaft 21. The lower ends of the shafts 18 are mounted in bearings 22 which are fastened to a plate 24 by means of screws 25. Mounted on the machine frame 12 above the gear box 16 is a cylinder 26 containing a piston 28 which is connect-

2

ed to the gear box by a piston rod 30. Fluid conduits 32 and 33 admit pressure fluid to the top and bottom of cylinder 16.

As best shown in Figure 4, a sleeve 34 surrounds each of the bushings 22 and is attached to the plate 24 in any suitable manner. The lower end of the sleeve is provided with two bayonet slots 36, each of which receives a pin 38 which is rigidly connected to a flexible shield 40 for movement therewith. The bottom of the shaft 18 extends into the sleeve 34 and has a transverse opening 42 extending therethrough. The shield 40 surrounds a flexible shaft 44 which has a bushing 46 brazed or otherwise fastened to its end, the bushing being provided with diametrically opposite holes 48 through its walls. A floating pin 50 passes through the holes 42 and 48 to connect the drive shaft 18 to the flexible shaft 44. The other end of the flexible shaft 44 is brazed to a bushing 52 whose lower end is internally threaded at 54 to detachably receive a drill 56 which is guided in a drill bushing 58 supported in a drill plate 60. Since it may be desired to use drills of different sizes and to vary the size of the drill bushing accordingly, the drill bushing is detachably connected to the drill plate 60 by the screws 61. The plates 24 and 60 are connected by means of a unitary portion 62 which is bolted to the machine frame 12 as shown. In order to make sure that the outer ends of the plates will remain in the desired position the ends are connected by the member 63. Surrounding the guide bushing 58 and attached to the drill plate 60 is a sleeve 64 whose upper end is provided with two bayonet slots 66 for receiving pins 68 which are rigidly connected to the lower end of the flexible shield 40. It will be seen that the top and bottom connections of the shield 40 are similar and permit ready removal or attachment of the shields. Beneath the drill plate 60 is a movable fixture 70 for supporting a plurality of workpieces. As shown, the fixture 70 has a plurality of openings 72 of various sizes and shapes for receiving workpieces 45 of corresponding shape. If desired, additional hold down means may be provided for preventing movement of the workpieces. Fastened to the fixture 70 are a plurality of guide rods 74 which extend upwardly into guide openings 78 in the drill plate 60.

When it is desired to drill holes at an angle to the horizontal it is only necessary to attach a vertical member 80 to the bottom of the drill plate 60 and attach a sleeve 64 and bushing 58 thereto. A flexible shield 40, enclosing a flexible

shaft 44, having a drill connected thereto, is passed through an opening 79 in plate 60 and attached to the sleeve 64 in the manner described above.

The fixture 70 is mounted on a piston rod 82 which is actuated by the movement of piston 84 in a cylinder 86. Fluid conduits 88 and 90 admit pressure fluid to the top and bottom of the cylinder 86. In order to fully utilize the drilling machine, it is desirable to have a plurality of fixtures 70 so that one may be loaded ready for movement under the drills after the workpieces in the fixture already under the drills have been drilled. For this purpose, the fixtures 70 are mounted for vertical movement in openings 92 provided in a turn table 93 which rotates about the shaft 94. The walls of the openings 92 are provided with liners 96 which closely fit the sides of fixtures 70 and cooperate with the guide rods 74 to guide the fixture in its vertical movement. The turn table 93 is provided with a gear 98 around its periphery which meshes with a pinion 100 mounted on a shaft 102, supported in bearing 104. The shaft 102 is driven from a drive shaft 106 through bevel gears 108. The turn table 93 is mounted on antifriction bearings 110 and may be provided with a brake for holding it against movement when desired.

In order to better provide for alignment of the drill and the work the drill plate may be adjustably mounted as shown in Figure 6. Instead of fastening the drill plate 60 directly to the members 62 and 63, an open frame 112 is connected to these members and the drill plate 60 is supported therein. Screws 114 passing through the walls of the member 112 are adjusted to position the plate 60 in the desired position after which it is clamped in place by moving wedges 116 inwardly along the tapered portions 118 of the frame 112 by means of screws 120. If desired, a ledge may be provided around the walls of the frame 112 to support the drill plate 60 during adjustment thereof.

The operation of the device is as follows:

Workpieces W are placed in the openings 72 in one of the fixtures 70 when in its loading position and the turn table 93 is then rotated by means of gear 98 and pinion 100 from the shaft 106 until the loaded fixture 70 comes under the drill plate 60. Suitable well known means may be provided for indexing the fixture 70 to this position. Flexible shafts 44, having the desired size of drill fastened thereto, are then connected to the drive shafts 18 as disclosed above and a flexible shield 40 placed around each shaft 44 and connected to the sleeve 34. The shafts 44 and shields 40 are of substantially greater length than the distance between plates 24 and 60 so that they may easily be moved to the desired position. After the drill plate 60 is positioned above the fixture 70, the lower ends of the shields 40 are attached to the sleeves 64 which are in the desired position above the workpiece. Pressure fluid is then supplied to the bottom of the piston 84 through the conduit 90, the fluid above the piston exhausting through the conduit 88. The fixture 70 is guided in its upward movement by the line 96 and the guide rods 74 in the openings 78. This rapidly moves the fixture 70 to a position adjacent the drill plate 60, after which pressure fluid is supplied to the top of piston 26 through fluid conduit 32, the fluid below the piston exhausting through the conduit 33. This moves the drive shafts 18 and the drills 56, attached to the flexible shafts 44, downwardly

through the flexible shields 40, the drills being guided into the workpieces by the bushings 58. If it is desired to drill only vertical holes in the workpiece, the drills 56 may be made long enough to extend below the bottom of the bushings 58 in normal position so that they will pass through the workpiece when the fixture 70 is moved upwardly by the piston 84 and the vertical movement of the shafts 18 may be omitted. However, when drilling holes horizontally as well as vertically, the movement of the shafts 18 is necessary to force the drill into the workpiece. When the drilling has been completed, pressure fluid is supplied to the bottom of piston 28 and to the top of piston 84 to return the parts to their original position. Meanwhile, another fixture 70 has been loaded and the turn table 93 is indexed so that the newly loaded fixture comes under the drills. If the second fixture is loaded in the same manner as the first, the drilling operation is repeated at once. If loaded in a different manner, the drills 56 must first be moved to pass through other of the bushings 58 in order to give the desired arrangement of holes. In some instances it may be necessary to replace the drills with a drill of a different size, in which case the drill bushing is replaced by one of the required size. When the drills have been arranged in the required design, the drilling operation is repeated. In some instances it may be desired to replace the drill plate 60 with a drill plate having a different arrangement of holes, this enabling a greater variety of workpieces to be drilled.

It will be seen that my invention is very flexible and enables a large number of different types of workpieces to be drilled, since the drills are easily moved from one drive shaft to another and from one guide bushing to another.

While one embodiment of my invention has been shown and described, it will be apparent that other adaptations and modifications may be made without departing from the scope of the following claims.

I claim:

1. A drilling machine or the like comprising a plurality of drive shafts, a plate having openings therein through which the drive shafts pass, a sleeve surrounding each of said drive shafts and attached to said plate, a drill plate spaced from said first named plate, said drill plate having a plurality of openings therein through which the tools pass, a sleeve connected to said drill plate at each of the openings therein, a plurality of flexible shafts, a bushing at each end of each flexible shaft, the bushings at one end of said flexible shafts being adapted to fit over the ends of said drive shafts, means for detachably connecting each drive shaft to the associated bushing, a tool connected to the second bushing of each shaft, a flexible shield surrounding each of said flexible shafts, the inside diameter of said flexible shields being approximately the same as the outside diameter of said bushings, said sleeves having bayonet slots therein, a pin at each end of each flexible shield adapted to be received in the corresponding bayonet slot, means spaced from said drill plate for supporting a workpiece, and means for moving said tools and flexible shafts through said flexible shields.

2. A drilling machine or the like comprising a plurality of drive shafts, a plate having openings therein through which the drive shafts pass, a sleeve surrounding each of said drive shafts and attached to said plate, a drill plate spaced from said first named plate, said drill plate having a

plurality of openings therein through which the tools pass, a sleeve connected to said drill plate at each of the openings therein, a plurality of flexible shafts, a bushing at each end of each flexible shaft, the bushings at one end of said flexible shafts being adapted to fit over the ends of said drive shafts, means for detachably connecting each drive shaft to the associated bushing, a tool connected to the second bushing of each shaft, a flexible shield surrounding each of said flexible shafts, the inside diameter of said flexible shafts being approximately the same as the outside diameter of said bushings, means for detachably connecting the flexible shields to said bushing, means spaced from said drill plate for supporting a workpiece, and means for moving said tools and flexible shafts through said flexible shields.

3. A drilling machine or the like comprising a gear box, a plurality of drive shafts mounted in said gear box for movement therewith, a plate having openings therein through which the drive shafts pass, a sleeve surrounding each of said drive shafts and attached to said plate, a drill plate spaced from said first named plate, said drill plate having a plurality of openings therein through which the tools pass, a sleeve connected to said drill plate at each of the openings therein, a plurality of flexible shafts, a bushing at each end of each flexible shaft, the bushings at one end of said flexible shafts being adapted

to fit over the ends of said drive shafts, means for detachably connecting each drive shaft to the associated bushing, a tool connected to the second bushing of each shaft, a flexible shield surrounding each of said flexible shafts, the inside diameter of said flexible shields being approximately the same as the outside diameter of said bushings, said sleeves having bayonet slots therein, a pin at each end of each flexible shield adapted to be received in the corresponding bayonet slot, means spaced from said drill plate for supporting a workpiece, and means for moving said gear box toward said first named plate to feed tools and flexible shafts through said flexible shields.
